(57) **CLAIM**

The ornamental design for the rocking chair, as shown and described.

DESCRIPTION

FIG. 1 is a front, right perspective view of a rocking chair showing my new design;

FIG. 2 is a front elevational view thereof;

FIG. 3 is a rear elevational view thereof;

FIG. 4 is a top plan view thereof;

FIG. 5 is a bottom plan view; and

FIG. 6 is a right side elevational view there, the left side being a mirror image thereof.
